UNITED STATES PATENT OFFICE.

FRANK KUHN AND JAY A. HAND, OF DETROIT, MICHIGAN, ASSIGNEES TO AMERICAN ELECTRICAL HEATER COMPANY, OF DETROIT, MICHIGAN, A CORPORATION OF MICHIGAN.

DESIGN FOR AN ELECTRICAL HEATER.

53,684.

Specification for Design.

Patented Aug. 5, 1919.

Application filed June 15, 1918. Serial No. 240,242. Term of patent 14 years.

To all whom it may concern:

Be it known that we, FRANK KUHN and JAY A. HAND, both citizens of the United States of America, residing at Detroit, in the county of Wayne and State of Michigan, have invented a new, original, and ornamental Design for an Electrical Heater, of which the following is a specification, refer-

ence being had therein to the accompanying drawings, forming part thereof, in which the figure is a perspective view.

We claim:

The ornamental design for an electrical heater substantially as shown.

FRANK KUHN.
JAY A. HAND.
